RESILIENT MOUNTING FOR A PLURALITY
OF MACHINESAlbert G. Dean, Narberth, Pa., assignor to The
Budd Company, Philadelphia, Pa., a corpora-
tion of Pennsylvania

Application October 5, 1949, Serial No. 119,636

7 Claims. (Cl. 105—133)

1

This invention relates to machine mountings, particularly to resilient mountings for a plurality of machines having different vibration frequencies and one or more of which may have an extraneous torque connection, and has for an object the provision of improvements in this art.

The invention has been developed and will be discussed in connection with a resilient mounting for a generator and compressor beneath a rail car, one of these machines being driven externally, as by an engine, and being connected in driving relationship with the other machine. The machines have different types and periods of vibration, hence if they were separately mounted and then connected in mutual driving relationship, as by a belt, it would be difficult to maintain proper driving relationship between them. To avoid this trouble, the present invention provides a common mounting for the two machines.

The machines may also be of different weights as well as of different vibration characteristics, hence they are mounted on a support which provides a general balance of moments. This not only furnishes a static balance when the machines are not operating but absorbs the different types of operational vibrations better than would a support with arms of equal length for the unequal weights. A resilient stay or guy rod is provided to resist unbalanced vibratory forces and the torque created through the extraneous driving connection.

The objects and various novel features of the invention will be apparent from the following description of an exemplary embodiment thereof, reference being made to the accompanying drawings, wherein:

Fig. 1 is a plan view taken just above the floor pans or channel cross floor beams of a railway car, with parts cut away to show apparatus mounted therebeneath;

Fig. 2 is a vertical section and elevation taken on the line 2—2 of Fig. 1;

Fig. 3 is a side elevation and section taken on the line 3—3 of Fig. 2;

Fig. 4 is a perspective view of the mounting frame alone;

Fig. 5 is an enlarged vertical section of one resilient support element, the section being taken on the line 5—5 of Fig. 3; and

Fig. 6 is an enlarged vertical section taken about on the same plane as Fig. 2 and indicated by the zone 6 of Fig. 2 but having parts broken away.

In the drawing the center sill of a car is indicated by the numeral 10, the floor pan or floor

10

channel cross beams by the numeral 11 and the side sill by the numeral 12. To the center sill there are secured, as by rivets, a number of de-

pending brackets 13 having loop-like depending

portions 14 for supporting equipment which will

be described.

The equipment to be supported may comprise a compressor 17 and a generator 18. The compressor may supply compressed air for brakes and the generator may supply electric current for car lighting and battery charging. One or the other of the devices 17, 18, here the generator 18, is driven by a prime mover, for example a diesel engine or the car axle (not shown), as by a shaft 19 having flexible couplings 20, and this then drives the other through belting 21 and pulleys 22, 23. If the car carries two prime movers and one or both should be disabled, it is possible to have the generator (having suitable characteristics) act as a motor operating on current from the other generator of the car or from battery to continue to drive the compressor, suitable known one-way drive means being incorporated in the shaft 19 so it will not be necessary to drive the main prime mover. The large size of the shaft indicates the presence of such a one-way drive device such, for example as an overrunning clutch device.

The devices 17 and 18 are of different weight, have different speeds and vibration characteristics and, as stated, to one of them driving torque, which in itself may be vibrating, from outside their support is applied, as by the shaft 19. It is desirable to minimize the total vibration on the car, however, and this is done here by mounting the devices together on a resilient support so that their combined inertia will resist the various vibrations which are normally out of phase and the resultant vibrations are damped

35 in the resilient mounting. The devices are mounted at such distances on each side of an intermediate point of support as to form substantially equal weight-arm moments to balance each other about the support.

As herein shown, a frame 25 is mounted on the bracket loops 14 by bolts 26 and resilient sleeve elements 27, such as rubber, placed in shear. The frame comprises ribs 28, some of which are L-shaped and extend out laterally to support one of the devices, as 17, and a bent plate 29 secured, as by welding, to the vertical parts of the ribs. The plate includes a top flange 30 having holes in which the bolts 26 are secured. The resilient element of rubber or the like is preferably bonded to an inner sleeve 31 and an outer sleeve 32,

2

the latter having a supporting flange 33 at the upper end. A large washer 34 is placed on the bolt to act as a safety support in case the resilient sleeve should fail or yield too far.

The device 18 may be mounted on a bracket 36 which is bolted to the vertical plate, as by bolts 37. The bracket may be considered as a part of the general supporting frame for the two devices 17, 18.

Unbalancing forces, such for example as the torque through shaft 19, the sway of the car, the action of centrifugal force and gravity as the car turns curves, and the like, may be taken by a brace or guy rod 40 secured at one end to the frame 25 and at the other end to the side sill 12 of the car. The connection to the frame is through a bent bracket 41 located, longitudinally, at about the center of mass of the devices 17, 18 and their supporting frame. Resilient elements 42, as of rubber, are connected between the reduced bolt-like ends of the rod and the anchorages therefor. The resilient elements may comprise separate rubber washers sandwiching between them the anchor element, with a metal sleeve 44 inside and washers 45 on the ends clamped between nuts 46 on the rod ends.

The anchor bracket 41 at the lower end has already been noted. At the upper end a bracket 50 serves as the anchorage, the bracket being welded to a bent stiffener 51 as by arc weld 30 fillets 52 and being hung at the other end on the inturned flange of the car side sill. A stiffener plate 53 is resistance-welded to the vertical plate of the side sill and the heavy bent stiffener 51 is secured to the floor and to the plate 53, as by 35 plug welds 54. At one or both ends of the assembly an end cap 55 is secured as by edge arc-welding 56. The end cap greatly stiffens the box assembly thus created.

In operation, the vibrations of the devices are 40 resisted by their combined inertia and absorbed in the resilient mountings so that little vibration is felt or heard in the car. The parts are balanced in a single plane of support and braced on the side so as to throw all the forces on the 45 center sill with none of any appreciable magnitude in the floor pans and side sill. The mounting is very simple and inexpensive and easy to install or remove.

While one embodiment has been illustrated and described it will be understood that there may be various embodiments within the scope of the invention.

What is claimed is:

1. A machine mounting, as for mounting machines beneath a rail car, in combination, a center sill, a base resiliently supported from said center sill at a point between the ends of the base, a compressor machine mounted on said base at one side of its point of support, a generator machine mounted on said base at the other side of the point of support, the weight of the compressor multiplied by its effective lever arm and the weight of the generator multiplied by its effective lever arm producing moments about said point of support which are approximately equal, a drive connection between said generator and compressor, a torque drive connection between one of said machines and a device mounted off said base beneath the car, a side sill, and a resilient guy rod between said base and said side sill.

2. A machine mounting, as for mounting machines beneath a rail car, in combination, a base 75 resiliently mounted at a point between its ends

beneath the car, a compressor machine mounted on the base at one side of the point of support and a generator machine mounted on the base at the other side of the point of support, the machines making approximately equal moments about the point of support, a drive connection between the machines, and a torque drive connection between one of the machines and an extraneous machine mounted beneath the car.

3. A machine mounting, as for mounting machines on a rail car, in combination, a base having an upstanding intermediate part and a support part extending outward from each side of the lower portion of the intermediate part, resilient swingable suspension means for the upper portion of said intermediate part, machines mounted on the support parts, a torque drive connection between one of said machines and an outside machine, and a resilient guy rod connected between said base and a fixed part on the car.

4. A machine mounting for a plurality of machines, comprising in combination, a base supported on a fixed part between machines carried thereon at a point which provides approximately equal moments on each side of the point of support, torque drive means between one of the machines from an outside device, a drive connection between machines on opposite sides of the point of support, and a guy member connecting said base to a fixed part.

5. A machine mounting comprising in combination, a frame including a base and an upwardly extending stem on said base, said stem being resiliently supported by rubber-like cushions at its upper end upon a fixed part for limited lateral and vertical movement, a machine supported on said frame at each side of the stem, and a brace member having resilient anchorages at each end connecting the base to a fixed part.

6. A machine mounting comprising in combination, a frame including a base and an upwardly extending stem on said base, said stem being resiliently suspended by rubber-like cushions at its upper end upon a fixed part for limited lateral and vertical movement, a machine supported on said base at each side of the stem, a torque drive between an outside device and one of said machines, and a brace member having resilient anchorages at each end connecting one side of the base to a fixed support.

7. A machine mounting comprising in combination, a frame including a base and an upwardly extending stem on said base, said stem being resiliently suspended by rubber-like cushions at its upper end upon a fixed part, a compressor machine supported on the frame at one side of the stem, a rotary electric machine supported on the frame at the other side of the stem, a driving connection between the machines, said machines being approximately balanced about the point of suspension, a torque driving connection between one of said machines and an outside device, and a resilient lateral connection between the lower part of the frame and a fixed part.
